FILING DEVICE

Oscar Stolp, Brooklyn, N. Y.

Application March 20, 1937, Serial No. 132,037

3 Claims. (Cl. 129—4)

This invention relates to a bill file or the like having a filing pin on which the papers are impaled.

An object of the invention is to provide a file of the above type having means to protect the point of the filing pin so as to prevent injury due to external contact therewith.

Another object is to provide a filing device of the above type in which the means for protecting the point of the filing pin also serves to push the papers to be filed down over the point of the filing pin.

Another object is to provide such a device having means for readily removing the papers from the filing pin.

Various other objects and advantages will be apparent as the nature of the invention is more fully disclosed.

Although the novel features which are believed to be characteristic of this invention will be more particularly pointed out in the claims appended hereto, the invention itself as to its objects and advantages and the manner of its organization will be better understood by referring to the following description, taken in connection with the accompanying drawing, in which certain specific embodiments of the invention are set forth for purposes of illustration.

In the drawing:

Fig. 1 is a side elevation, partly in section, of a filing device embodying the present invention.

Fig. 2 is a front elevation thereof.

Fig. 3 is a horizontal section taken along the line 3—3 of Fig. 1.

Referring to the drawing more in detail, in the embodiment shown in Figs. 1 to 3 the invention is shown as comprising a base 10 carrying a bracket 11 to which a housing 12 is secured. The housing 12 is provided with side members 13 in which a rod 14 is pivotally held, as by screws 15. A filing pin 16 is secured in the rod 14 and extends upwardly through an aperture 17 in the housing 12. A spring 18 is disposed around the rod 14 to normally hold the filing pin in vertical position against the edge 20 of the aperture 17. The aperture, however, is sufficiently long to permit the pin to be bent outwardly as indicated in dotted lines in Fig. 1 when the papers are to be removed therefrom. The pin 16 extends upwardly and is provided with a point 21 at the top end thereof, which is adapted to receive the papers for filing in the usual manner.

The bracket 11 extends upwardly and is provided with a bent over flange 25 which extends over the point of the pin 16 when the pin is in

vertical position, so as to form a guard for the purpose specified. A clip 26 is pivotally attached to a hinge 27 which is secured to the bracket 11. This clip 26 extends outwardly from the bracket 11 over the point of the pin 16 and normally bears against the end of the flange 25, in which position it is held by a spring 30. The clip 26 extends outwardly past the flange 25 and is provided with a flange 31 which is adapted to be engaged by the finger when the clip 26 is to be depressed. The clip 26 is provided with an aperture 32 which is of suitable shape to permit passage of the point 21 of the pin 16 when the clip is depressed.

A sleeve 33 may also be provided on the pin 16 for receiving the papers for filing and is adapted to be removed with the papers to form a permanent file. The sleeve 33 is provided with a bottom flange 34 which prevents the papers from falling off of the sleeve when the latter is removed from the pin 16.

In the operation of the above described device, when it is desired to apply a paper to the file, the edge of the paper is pushed over the point 21 of the pin 16 and under the clip 26. With the same motion the clip 26 is depressed by engaging the same with the finger, thereby causing the aperture 32 to extend downwardly over the point 21 and to perforate the paper and start the same down over the pin. The paper may then be pushed down over the pin in the usual manner.

It is to be noted that the file can be used as conveniently as an unguarded file as no additional motions are required in applying a paper thereto. The hand, however, cannot come in contact with the point of the filing pin. The clip 26 serves the double purpose of guarding the point of the pin and at the same time perforating the paper and starting the same down over the pin.

The papers can be removed together for permanent filing by sliding the sleeve 33 from the pin 16, the pin being bent outwardly as indicated in dotted lines in Fig. 1 for this purpose. It is to be understood, however, that the sleeve 33 may be omitted if this feature is not desired. It is further to be understood that the particular construction of the clip 26 and of the housing 12 may be varied as desired.

Although a specific embodiment of the invention has been shown for purposes of illustration, various changes and modifications may be made therein, as will appear to a person skilled in the art. The invention is accordingly to be limited

only in accordance with the following claims, when interpreted in view of the prior art.

I claim:

1. A filing device for papers or the like, comprising a filing pin, a bracket supporting said pin and a plate hinged to the bracket and extending over the point of the pin, said plate being depressible and having an opening to receive the point of the pin so as to perforate a paper which is to be filed and to start the paper down over the pin, said bracket having a rigid flange extending over the point of said pin above said plate for shielding the pin and forming a stop for normally holding said plate in position above said pin.
2. A filing device for papers or the like, comprising a filing pin, a bracket supporting said pin and a plate hinged to the bracket and extending over the point of the pin, said plate being depressible and having an opening to receive the point of the pin so as to perforate a paper which is to be filed and to start the paper down over the pin, said bracket having a rigid flange

extending over the point of said pin above said plate for shielding the pin and forming a stop for normally holding said plate in position above said pin, said plate extending beyond said rigid flange to form a flange which is adapted to be engaged by the fingers for depressing the plate when the papers are to be filed. 5

3. A filing device for papers or the like, comprising a filing pin, a bracket supporting said pin and a plate hinged to the bracket and extending over the point of the pin, said plate being depressible and having an opening to receive the point of the pin so as to perforate a paper which is to be filed and to start the paper down over the pin, said bracket having a rigid flange extending over the point of said pin above said plate for shielding the pin and forming a stop for normally holding said plate in position above said pin, said pin being hinged to said bracket to be movable about a horizontal axis whereby the point of the pin is disengaged from beneath said plate to permit papers to be removed therefrom. 10 15 20
